UNITED STATES PATENT OFFICE.

FREDERICK H. N. GERWIG, OF BRADDOCK, PENNSYLVANIA.

HOT-BLAST-STOVE APPLIANCE.

1,175,629.

Specification of Letters Patent. Patented Mar. 14, 1916.

Application filed May 15, 1915. Serial No. 28,343.

To all whom it may concern:

Be it known that I, FREDERICK H. N. GERWIG, a citizen of the United States, and resident of Braddock, in the county of Allegheny and State of Pennsylvania, have invented certain new and useful Improvements in Hot-Blast-Stove Appliances, of which the following is a specification.

My invention relates to appliances used in supplying air and blast furnace gases to the combustion chambers of hot blast stoves for blast furnaces, in heating the stove checkerwork. In the use of such hot blast stoves, the air blast is heated by passing the air blast through the stoves while under a pressure of between 1 and 2 atmospheres, the air absorbing heat from the highly heated checker work in passing through the refractory checker work of the stove to the hot blast main leading to the blast furnace. In heating the checker work, between the intervals in which the cold air blast is being heated, a mixture of air and blast furnace gas, at about atmospheric pressure, is burned within the stove combustion chamber, the heated products of combustion passing therefrom through the checker work and out through the stack and heating the checker work in its passage therethrough.

With existing appliances used in heating the checkers of hot blast stoves for blast furnaces the volume of air mixed with the burning gases in heating the stove is dependent upon the draft of the stove stack, and in many cases the amount of air is found to be insufficient.

One object of my invention is to provide a hot blast stove appliance of novel construction having improved means whereby the quantity of air supplied to existing stoves is materially increased.

Another object of my invention is to provide a hot blast stove appliance for supplying a mixture of blast furnace gases and air to the combustion chamber of a hot blast stove, having novel means whereby the gases used as fuel in heating hot blast stoves and the air are thoroughly mixed and commingled, and the volume of air and gas supplied to the stoves is materially increased.

A further object of my invention is to provide a hot blast stove appliance having improved means whereby the volume of air

supplied to the combustion chamber of the stove is regulated and controlled.

Still further objects of my invention will become apparent as will be more fully described hereinafter and particularly pointed out in the appended claims.

Referring now to the drawings forming part of this specification, Figure 1 is a side elevation, partly in section, showing a hot blast stove appliance constructed and arranged in accordance with my invention, and in operative position relative to the gas inlet leading to the combustion chamber of the stove. Fig. 2 is a plan, partly in section, of the apparatus shown in Fig. 1. Fig. 3 is an end elevation of the apparatus shown in Figs. 1 and 2.

In the accompanying drawings the numeral 2 designates a hot blast stove (of the two pass type) having a lengthwise vertical side combustion chamber 3 on the lower end of which is a gas inlet 4 leading into the bottom of the combustion chamber. At one side of the stove is a vertical gas flue 5 leading from an overhead horizontal gas main of the usual construction (not shown) to the gas box 6 located on the ground level at the base of the stove 2.

The gas box 6 is provided with a flanged branch outlet 7 which is connected by a pipe 8 with the lower end of the pipe or conduit 9, and the upper end of the conduit 9 is provided with a flange 10 forming the seat or support for the sliding burner pipe 11 which forms part of my improved stove 99 appliance. The burner pipe 11 is circular in cross section and has flanges forming a slide 12 on one end which rest on the support 10 formed on the upper end of the conduit 9. The burner pipe 11 has an opening 13 in its side wall at the rear end thereof which when in open or gas discharging position registers with the similar opening 14 in the upper end of the conduit 9. A shelf or bracket 16 on the upper end of the pipe 100 9 provides a support for the pipe 11 and also forms a shutter for the opening 13 when the conduit is in retracted position, the burner pipe being arranged to move lengthwise on the end of the conduit 9 into 105 and out of gas supplying position, which latter is shown in Figs. 1 and 2.

A lever 17 is keyed or otherwise secured on the shaft 18 and connected by a link 19 with the burner pipe 11, and a burner pipe 110

operating lever 20 loosely mounted on one end of the shaft 18 is provided with a ratchet pawl 21 which operatively engages with the ratchet wheel 22 on this end of the shaft 18 in moving the sliding gas pipe 11 off its seat formed by the flanges or shelves 10 and 16 on the open upper end of the conduit 9.

Secured within the burner pipe 11 so as to be axially in alignment therewith, with one end projecting through the opening in the rear end of the burner pipe 11, is a smaller air conduit 23 through which the air under a slight pressure is supplied to the combustion chamber 3 of the stove to be mixed with the annular stream of blast furnace gases issuing from the burner pipe 11 in burning the gases within the combustion chamber. The rear end of the air conduit 23 is connected by the connected elbows 24 and 25 with the outlet opening 26 of a rotary fan or blower 27. Mounted on brackets 28, 28, formed integrally on top of the burner pipe 11 is a base plate 29 on one end of which the fan 27 is mounted, and on the other end of the base plate 29 is a variable speed electric motor 30. The armature shaft 31 of this motor is connected by a flexible coupling 32 with the driving shaft 33 for the blades of the fan 27. The inlet to the fan or blower 27 has a screen 34 therein to prevent dirt or other solids floating in the atmosphere being drawn into the fan when the fan is in operation.

An annular plate 34 loosely mounted on the end of the burner pipe 11 provides means for regulating the volume and shutting off the supply of air induced to flow into the inlet 4 by the action of the gases entering the stove through the burner pipe 11.

From the above description it will be readily seen that the motor and fan are permanently secured on top of the movable burner pipe 11 so as to move with this pipe when the pipe is shifted into and out of its operative position shown in the drawings.

In the operation of my improved apparatus the burner pipe 11 is shifted by means of the hand lever 20 into position so that its front or forward end projects into the gas inlet 4 leading into the combustion chamber 3 of the hot blast stove 2. When movement of the pipe 11 into the position shown is started the motor 30 also is started so as to drive the fan or blower 27, and supply air under pressure through the pipe 23 to the inlet 4.

As the burner pipe 11 moves lengthwise on the shelves or supports 10 and 16 the opening 13 in the pipe 11 begins to register with the opening 14 in the upper end of the conduit 9 so as to admit gases from the flue 5 and gas box 6 into the annular burner pipe 11. An annular stream of gases flows through the gas inlet 4 into the combustion chamber

3 of the stove and in passing through the inlet 4 becomes thoroughly mixed with the air entering the combustion chamber from the air conduit 23. The volume of air entering through this conduit will vary with the pressure and both will vary with the speed at which the fan 27 is driven, so that both the volume and pressure of the entering air is readily regulated and controlled by changing the speed of the variable speed motor 30 which drives the fan 27. The regulated amount of air supplied in this way insures a more complete combustion of the gases burned in the combustion chamber.

When it is desired to utilize the stove to heat the cold blast, the burner pipe 11 is moved backwardly until its forward end is clear of the outer end of the inlet 4 on the stove 2. In moving the pipe 10 backwardly, which is done by means of the handled lever 20, the opening 13 in the side wall of the pipe 11 will be brought into position above the shelf 16 on the conduit 9 and in this way shut off the supply of gases from the gas box 6 to the pipe 11. The motor 30 will then be stopped by throwing a suitable switch on the feed wires connecting the motor with a source of electric current in the usual known manner. The opening 4 is then closed by means of a suitable head (not shown) and the cold blast inlet and hot blast outlet on the stoves are opened to admit cold blast and permit the passage of the hot blast from the stove into the hot blast main leading to the bustle pipe of the furnace, the blast being heated in passing through the stove checker work in the usual manner.

The advantages of my invention, which will be readily appreciated by those skilled in the art, arise from the self-contained appliance by which air is supplied to the stove for mixing with the blast furnace gases in burning the gases in regulated quantities and at a regulated pressure. The provision of the motor driven fan on the burner pipe enables the volume of air supply to be increased on existing stoves and avoids the necessity of increasing the height of the stove stack to thereby increase the draft as would otherwise be necessary to increase the air supply to the stove combustion chamber.

The apparatus is simple, is easily operated, and is easily and cheaply kept in repair.

Modifications in the construction and arrangement of the apparatus may be made without departing from my invention as defined in the appended claims.

I claim:

1. In a hot blast stove the combination with the stove of a sliding burner pipe for supplying air and gas to the stove combustion chamber, said burner pipe having a central air conduit and an annular gas conduit surrounding the air conduit, means for supplying gas to the annular gas conduit, a

motor driven fan mounted on the burner pipe to move therewith, means connecting the fan outlet and air conduit to supply air under pressure to said burner pipe, and means for moving said burner pipe into and out of position relative to the combustion chamber of said stove.

2. In a hot blast stove the combination with the stove of a burner pipe for supplying air and gas to the stove combustion chamber, said burner pipe having air and gas conduits therein, a gas supply pipe on which said burner pipe is movably mounted, a motor driven fan mounted on the burner pipe and movable therewith, a pipe connecting the fan outlet and air conduit on said burner pipe for supplying air under pressure to said burner pipe, and means for moving said burner pipe on the gas supply pipe in regulating the gas supply to the gas conduit.

3. In a hot blast stove the combination with the stove of a burner pipe for supplying air and gas to the stove combustion chamber, said burner pipe having a central air conduit and an annular gas conduit surrounding the air conduit, a gas supply pipe

on which said burner pipe is movably mounted, a motor driven fan mounted on the burner pipe and movable therewith, a pipe connecting the fan outlet and air conduit on 30 said burner pipe for supplying air under pressure to said burner pipe, and means for moving said burner pipe on the gas supply pipe in regulating the gas supply to the gas conduit.

4. In a hot blast stove, the combination with the stove of a burner pipe for supplying air and gas to the stove combustion chamber, said burner pipe having separated air and gas conduits therein, a gas supply 40 pipe connected to the gas conduit, a fan mounted on the burner pipe, an air pipe connecting the fan outlet and air conduit for supplying air under pressure to said burner 45 pipe and a variable speed motor for driving said fan.

In testimony whereof, I have hereunto set my hand.

FREDERICK H. N. GERWIG.
